CLAIM

The ornamental design for a cap for fragrance bottle, substantially as shown and described.

DESCRIPTION

FIG. 1 is a front perspective view of a cap for fragrance bottle showing our new design;

FIG. 2 is a left side elevation view of the cap shown in FIG. 1;

FIG. 3 is a front elevation view of the cap shown in FIG. 1; FIG. 4 is a right side elevation view of the cap shown in FIG. 1;

FIG. 5 is a rear elevation view of the cap shown in FIG. 1; FIG. 6 is a top plan view of the cap shown in FIG. 1; and, FIG. 7 is a bottom plan view of the cap shown in FIG. 1. The broken lines are shown for the purpose of illustrating portions of the article that form no part of the claimed design.

1 Claim, 2 Drawing Sheets
